CONTINUOUS DELIVERY CHEMICAL WASH BOTTLE

Norman F. Floyd, Philadelphia, Pa., assignor to
The Lankenau Hospital, Philadelphia, Pa., a
corporation of Pennsylvania

Application August 22, 1946, Serial No. 692,169

1 Claim. (Cl. 23—292)

1

This invention relates to improvements in the art of continuous delivery of liquids from liquid-holding containers and particularly to a continuous delivery device for obtaining a continuous flow of liquid from a container such as a chemical wash bottle.

In the removal of liquids from containers and in cases where it is desired to make use of the stream of liquid being removed, there are occasions in which it is necessary to provide a positive control whereby the stream of liquid may be interrupted. For instance in the case of the wash bottles used in scientific laboratories the ejected stream of liquid is used to wash selected surfaces of the equipment being used. The simplest form of such a wash bottle consists of a flask to which is attached a stopper adapted to receive a pressure tube and a delivery tube. Delivery of the liquid is accomplished by applying pressure through blowing into the pressure tube. In this simple form of wash bottle the stream of liquid stops when the blowing into the pressure tube is interrupted. However, in many instances it is desired to use the stream of liquid from such wash bottles without the necessity of continuing to blow into the pressure tube. In such cases a continuous flow of liquid is required. Various means have been proposed for obtaining such a continuous flow. Of these proposals all have carried with them certain disadvantages which have arisen from the complications introduced in providing means for maintaining a continuous flow which can be caused to stop at will. For instance, the devices heretofore suggested in the chemical wash bottle field have included the use of materials which cannot withstand the action of the chemical liquids sometimes used and have also required additional holes in the stopper element, thus placing a further limitation on the type of stopper which must be employed. In this connection the device which the present invention would displace requires a cumbersome arrangement of three tubes, including a separate vent tube, all of which pass through the stopper. The present invention requires but two tubes and is much simpler both in construction and use.

In view of the above, one object of the present invention is to provide a continuous delivery attachment for obtaining a controlled stream of liquid from a container.

It is a further object of the present invention to provide a continuous delivery attachment for a liquid-holding container which attachment is simple in construction and readily controllable manually while in use to interrupt the flow of liquid.

2

Other objects and fields of use of the present invention will appear from the description which follows, reference being had to the accompanying drawings in which:

5 Fig. 1 is a vertical elevation partly in section; and

Fig. 2 is a partial vertical elevation, partly in section, of an alternative form of the invention.

Fig. 3 is a sectional view illustrating an alternative form of connecting joint.

10 Fig. 4 is a vertical elevation, partly in section, of an alternative form of the invention.

Fig. 5 is a side view as indicated by the arrows V—V in Fig. 4.

15 Fig. 6 is a partial vertical elevation, partly in section, of an alternative form of the invention shown in Fig. 4.

As shown in Fig. 1 the continuous delivery attachment of the present invention is adapted to be fitted to a flask 1 containing a liquid as shown

20 at 2. The attachment consists of a stopper 3 which may be constructed of glass, rubber, or the like, and which is adapted to fit tightly into the neck 4 of the flask. The stopper 3 is provided with two holes.

25 Associated with one hole is a pressure tube 5 having an upper branch 6 and a lower branch 7 which engages with the stopper as shown. The lower branch of the pressure tube 5 is provided with a valve seat 8 adapted to receive the tapered valve element 9 which is formed at the lower end of the valve stem 10. The valve seat 8 and the valve element 9 are ground to fit closely so that when the valve element is in a position engaging the valve seat, flow of air is prevented in the lower branch 7 of the pressure tube

30 5. In the upper branch 6 of the pressure tube 5 the valve stem 10 is closely fitted along the surfaces where it slidably engages the upper branch 6, and this close fit prevents the passage of air in the upper branch 6 at all times. This is important in the building up of pressure in flask 1.

35 At the upper end of the valve stem 10 there is provided a control head 11 for ease in the manual manipulation of the valve stem when the device is in use. A delivery tube 12 is provided which passes through the second hole provided in the stopper 3 and extends to the lower portion of the flask 1. Attached to the delivery tube by means of a flexible coupling 13 is a delivery jet 14 which has a constricted delivery tip for the more efficient production of a usable stream of liquid.

40 Where it is necessary to use liquids which would attack flexible couplings of the type shown at 13, the ball joint construction shown in Fig. 3 may be employed. In this form the delivery tip 45 14 terminates at the joint end in a rounded por-

tion 26 having a single opening 27. This rounded portion 26 engages element 28 in a liquid-tight joint but is free to rotate therein. There is thus provided a flexible joint which makes it possible to direct the stream of liquid emerging from the delivery tip 14 without restricting the flow at the joint.

The alternative form of the invention shown in Fig. 2 consists of a pressure tube 15 having an upper branch 16 and a lower branch 17. The lower branch 17 is provided with a valve seat 18 which is so constructed as to receive a valve element 19 adapted to be attached to the valve stem 20. For ease of assembly the valve element 19 may be internally threaded for attachment to a threaded end portion of the valve stem 20. Valve stem 20 extends upwardly within branches 17 and 16 of pressure tube 5 and passes through the valve stem guide 21 at the top of upper branch 16 where it is tightly fitted so as to prevent the passage of air. Valve stem 20 terminates at its upper end at an anchoring point 22 located at the upper inside surface of the control cap 23 which is likewise closely fitted to the contact surface of the upper branch 16 so as to prevent further the escape of air through the upper branch 16. A spring 24 is provided and also a spring seat 25 to which the lower end of spring 24 is seated. The upper end of the spring 24 engages the upper inside surface of the control cap 23 and forces it upwardly together with the valve stem 20 and the valve element 19. Consequently the normal position of the valve element 19 is such as to prevent the escape of air outwardly through the pressure tube 15. However, the degree of tension applied by the spring 24 is limited to a force which can be counteracted by the normal force of air under pressure applied through the pressure tube 15 by blowing, thus making it possible to blow air under pressure through pressure tube 15 and past valve element 19 thereby building up pressure in the flask 1. This results in a flow of liquid in delivery tube 12 and a consequent stream which issues from the delivery tip 14. If the blowing of air is discontinued, the valve element 19 is moved automatically to a closed position leaving a positive pressure within flask 1 which seeks equilibrium by forcing a stream of liquid out delivery tip 14.

The alternative form of the invention shown in Figs. 4 and 5 consists of a cap member 30 adapted to fit over the neck 31 of a flask 32. Attached to cap member 30 at its upper end is a delivery tube 33 terminating in a delivery tip 34. Communicating with delivery tube 33 and passing downward inside cap member 30 and flask 32 is a tube 35 terminating at the inner edge of the base of flask 32. Also attached to cap member 30 is a branched pressure tube 36 having an upper branch 37 and a lower branch 38. Positioned within said upper and lower branches is a valve element 39 which terminates in a tapered portion 40 adapted to engage valve seat 41 which is formed in the lower branch 38. Valve element 39 terminates at its upper end in an enlarged control surface 42 after curving downwardly as shown. In order to insure a snug fit of cap member 30 at all times, a pair of projections 43 are provided at the lower portion of the neck 31 and a corresponding pair of projections 44 are provided at the upper end of the cap member 30. Rubber bands 45 are provided for engagement with projecting members 43 and 44. Likewise projecting member 46 is provided on the branched pressure tube 36 and a second projecting mem-

ber 47 is provided at the upper end of valve element 39. Rubber band 48 engages projections 46 and 47 and holds valve element 39 securely in place.

5 The alternative form shown in Fig. 6 is similar to that shown in Figs. 4 and 5 except that cap member 30 has a tapered construction for engaging the neck 31 of flask 32 on its inner surface as a stopper as shown.

10 When it is desired to use the embodiment of the present invention shown in Fig. 1 the air pressure is supplied by blowing into pressure tube 5. In order for such air to provide a pressure in flask 1 it is necessary to lift valve stem 10 by means of its control head 11. When this is done air under pressure is admitted into the flask 1 through the lower branch 7, the escape of air through the upper branch being prevented by the snug fit provided between the valve stem 10 and the walls of the upper branch 6. As soon as sufficient air pressure has been developed within the flask 1 as evidenced by a steady stream of liquid from a delivery tube 12 the valve stem 10 is lowered thus shutting off the pressure tube 5 at the valve seat 8. No further pressure need now be applied to the pressure tube 5 since the pressure now developed in flask 1 can equalize only by forcing additional liquid out through the delivery tube 12. The flow of liquid will thus be continuous until such time as the loss of liquid reduces the pressure in the flask 1 to the pressure of the outside atmosphere. This period of time will be sufficiently long for the normal purposes to which the liquid stream will be put and therefore in the present specification the term "continuous" is applied to such delivery and to the device itself although it is recognized that a point will ultimately be reached at which the flow of liquid will cease. Normally the desired stopping point will be prior to the stopping of the liquid stream by equalization of pressure. Where this occurs the valve stem 10 is lifted thus allowing air under pressure to escape through the pressure tube 5. This sudden equalization of pressure serves to stop immediately the flow of liquid in delivery tube 12.

15 In the use of the alternative form of the invention shown in Fig. 2 it is not necessary to manipulate manually the valve element 19 at the start of the operation since air may be blown through the pressure tube 15 and the lower branch 17 past the valve element 19 by overcoming the slight tension produced on valve element 19 by the spring 24. It is thus only necessary to blow through pressure tube 15 until such time as a fluid stream emerges from delivery tube 12. At this point the blowing may be discontinued which will result in the immediate seating of the valve 20 in response to the action of spring 24 on the valve stem 20. This will leave a positive pressure within flask 1 which will act to produce the desired stream of liquid as described above. When it is desired to interrupt the flow of the stream of liquid thus produced it is only necessary to depress the control cap 23 which will result in the disengagement of valve element 19 from valve seat 18 with a consequent release of pressure through the pressure tube 15. This will have the effect of immediately shutting off the liquid stream emerging through delivery tube 12.

20 In the use of the alternative form shown in Figs. 4, 5, and 6 the control surface 42 is positioned above the thumb position of the user of the device. It is thus possible to disengage 25 valve element 40 from valve seat 41 by a slight

upward pressure of the thumb on control surface 42. Air under pressure is then applied by blowing into pressure tube 36. Continued pressure and therefore continued liquid flow is achieved by removing the pressure from control surface 42 thus allowing the rubber band 48 to cause valve element 40 to engage valve seat 41. The continuous flow from delivery tip 34 may be instantly discontinued by a re-application of pressure upwardly on the control surface 42. Since the control surface 42 is positioned just above the normal thumb position, the operation as described above may be carried out entirely with one hand leaving the other hand free. This is of particular advantage where the present invention is used in connection with a chemical wash bottle.

It will be seen that the device of the present invention has the great advantage of simplicity of construction thus making it possible to use a large variety of suitable materials. For instance, in the use of corrosive liquids all of the separate elements coming in contact with the contents of the flask may be made of glass. It is also possible to dispense entirely with the use of rubber. The invention also provides a great advantage in ease and simplicity of operation particularly in the operation of the means for discontinuing the stream of liquid easily and promptly. This is of great importance in the use of this device in connection with chemical wash bottles since the operator must be free to operate the wash bottle with one hand and at the same time must have positive and quickly accessible means for discontinuing the liquid stream at will with the same hand.

While I have shown and described two preferred embodiments of the present invention it will be understood that the device as shown may be modified without departing from the spirit or scope of the invention.

Having thus described my invention, I claim:

A chemical wash bottle and a fluid delivery attachment therefor comprising a closure element having openings therein, a delivery tube extending downwardly through one of said openings and terminating near the bottom of the wash bottle, a combined pressure and pressure-exhaust tube extending through another of said openings and terminating above the lower end of said delivery tube said pressure tube hav-

ing a vertical extension with an upper opening closed to the atmosphere and a laterally extending branch open to the atmosphere, a valve seat positioned in said pressure tube below the point at which said tube branches, a valve member engaging said seat having a manually operable rod extending upwardly through said vertical extension, and closure means for said vertical extension arranged to permit operation of said valve rod while maintaining the upper opening of said vertical extension substantially closed to the atmosphere.

NORMAN F. FLOYD.
